FLUID PUMP

Cecil C. Buckner, Grosse Pointe Park, Mich.

Application February 28, 1944, Serial No. 524,176

6 Claims. (Cl. 103—162)

1

The present invention relates to multicylinder fluid pumps and has among its objects a pump capable of large delivery at a constant pressure.

Another object is a pump of this type which shall be of relative small size and weight when considered in the light of its delivery volume.

Another object is a pump of this type which may easily and quickly be arranged to pump in the reverse direction.

Another object is a pump of the rotary type embodying structure adapted to eliminate vibration and stresses due to slight misalignment of the drive means.

Other objects and advantages will be apparent to those skilled in the art upon reference to the following description and the accompanying drawings in which:

Figure 1 is a partial side elevation with the major portion in central vertical longitudinal section.

Figure 2 is a top-plan view indicating diagrammatically certain of the internal passages.

Figure 3 is an end view from the left of Figures 1 and 2.

Figure 4 is an end view from the right of Figures 1 and 2.

Figure 5 is a view in elevation of the valve ring.

Figure 6 is a developed view of the inside of the same.

Figure 7 is a developed view of the inside of that portion of the housing surrounding the valve ring.

Figure 8 is a view of the piston guide ring as if taken on a line with line 8—8 of Figure 1.

Figures 9 to 14 are views of certain details of the pump structure.

Referring to the drawings, the pump is seen to consist of a rotor comprising two cylinder-carrying rings 20 and 20A fixed together with an interposed ring 21 of the form shown in Figure 8, the through parts being held together by through-bolts (not shown, but indicated by the openings 21A, Fig. 8). The ring 21 is provided with inwardly extending portions providing recesses 21B serving as guides for the piston connecting blocks 22.

In each of the cylinders in rings 20 and 20A is a piston 23 having a neck by means of which it may be connected to a block 22 through the use of a spring horseshoe washer 24, the block being provided with a suitable recess in its end and slotted to receive the washer.

The cylinders in ring 20 are arranged in axial alignment with those in ring 20A and also in alignment with recesses 21B. Each of the blocks 22 is supported within the housing by means of flanges 45 and 46, forming portions of rings 20 and 20A respectively, the flanges being mounted in suitable antifriction bearings, and is driven

2

22 is provided on its radially inward side with a notch adapted to coact with the gear-tooth shaped head 25 of a pin 26 of which there are as many, of course, as there are blocks 22.

These pins 26 are suitably mounted in the periphery of a cage 27, rotatably mounted upon a shaft 28, suitable antifriction bearings 29 being used, and said pins are all located in a plane at right angles to the axis of the shaft. Further, the cage 27 and rings 20 and 20A are provided with coacting spherical bearing surfaces 30, the center of which is in the axis of shaft 28 and in the centerplane of the pins 26. Shaft 28 terminates at one end within the spherical bearing 30, but its other end extends well beyond the cage 27, being offset as at 28A to permit the extension to move up and down a sufficient distance.

The outer ends of the cylinders in rings 20 and 20A are enlarged to receive the end closing 20, 20A, these being held in place by the use of a spring ring coacting with an internal groove in the enlargement and an external groove in the thimble, as indicated at 35A. These thimbles are of an internal diameter somewhat greater than that of the pistons 23 and do not extend the full length of the enlarged cylinder portion. There is, therefore, a small chamber 36 around the piston 23 when the latter is in its inward position, and, because of the larger inner diameter 30 of the thimble, this chamber extends also around the end of the piston.

From the portion of the chamber 36 surrounding the piston, a passage 37 extends to the periphery of the cylinder ring (20—20A) and opens into a groove 39 on the inner side of a valve ring 40 mounted with the housing and around the rotor closely adjacent the outer peripheries of rings 20 and 20A. This valve ring is shown in Figures 5 and 6, the latter being a developed view of the inside surface.

As shown, the groove 39 does not extend completely around the ring but is interrupted for a short distance at two diametrically opposite points 39A, and is open to the outer surface 45 through a plurality of openings 39B. One half of the groove 39, however, is extended completely around the ring by the small grooves 39C, the combined area of these being equal to the area of groove 39. These grooves 39C do not open to the outside of the ring.

The rotor, composed of the rings 20, 20A and 21 is supported within the housing by means of flanges 45 and 46, forming portions of rings 20 and 20A respectively, the flanges being mounted in suitable antifriction bearings, and is driven

through flange 45, which is provided with internal splines 45A adapted to coact with external splines 45B carried by member 47.

This member 47 is shown in detail in Figures 9 and 10, and constitutes a portion of a universal drive connection of which the other portions are shown in detail in Figures 11 to 14.

Member 47 consists of a sleeve portion 47A provided with an internal shoulder 47B and externally splined as at 45B. It also is provided at the end opposite the splines with an outwardly extending flange 47C, from which extend the diametrically opposite arms 48, extending radially and having their sides or edges parallel. This member 47 is adapted to coact with the ring 49, Figures 11 and 14, and the member 40, Figures 12 and 13 to form a universal joint.

The ring 49 consists of a relatively thick ring provided with an internal flange 49A in which are provided four notches 49B arranged 90° apart and of such width as to accurately fit the arms 48 on member 47 and the similar arms on member 50. The ring 49 is also provided with narrow grooves 49C in its inner periphery above and below the flange 49A and separated from each other a distance slightly greater than the thickness of the said arms.

The member 50 comprises a splined shaft portion 50A provided at one end with a disc portion 50B from the edge of which extend two arms 50C. These are diametrically opposite and of a size and shape to fit the notches 49B in ring 49. It is preferred to so proportion the notches 49B and arms 48 and 50C that, when the parts are assembled, there is permitted a small amount of relative movement between the ring 49 and the arms radially of the ring but not peripherally.

Assembly of the members 47, 49 and 50 is accomplished by placing in the grooves 49C, after the said arms are in the notches, the flat spring expanding rings 51 and, since these are spaced slightly from the upper and lower faces of the several arms, there is permitted a small relative angular movement of the parts 47 and 50.

The above assembly constituting the rotor drive is held in place with the splines 45A and 45B interspaced, by means of an externally threaded thimble or hollow screw 52 passing axially through member 47, its head coacting with the internal shoulder 47B and its threaded portion coacting with a nut 53 seated upon a suitable shoulder at the root of flange 45. A spring ring 53A is used to prevent loosening of nut 53.

The housing of the rotor consists of two parts, of which the part A consists chiefly of a mounting flange 55 by means of which the pump may be fixed upon a suitable support, and a sleeve portion in which is mounted the antifriction bearing 56 for the part 45 of the rotor, and means 57 for sealing this end of the pump. This means 57 may be of any suitable form of sealing ring, but as shown consists of an oil flinger plate 57A having ribs 57B mating with similar ribs on a stationary plate 57C, there being a packing ring 57D between the two. Oil thrown from the edge of plate 57A collects in an annular groove 58 and passes back into the housing through passages 58A.

The second portion B of the rotor housing carries at one end, means for mounting the antifriction bearing 56A serving to support the flange 46 of the rotor and within that portion surrounding the main part of the rotor is provided with fluid passages and with a suitable seat for valve

ring 40, the latter being maintained stationary by means of a press fit or other means.

The fluid passages referred to consist of a pair of passages arranged spirally within the wall of this portion B, one passage opening to the outer face of ring 40 over a groove 39 and leading thence to pump outlet (or inlet) 60. The other passage opens to the other groove 39 and leads to the other outlet (or inlet) 61.

These passages, indicated diagrammatically in Fig. 2, at 62 and 63, are shown best in Figure 7, and in the latter the inlet 60 is shown as connected to a long slotted opening 60A which overlies a groove 39 and through the spirally arranged passage 60B to a second long slotted opening 60C which overlies the other groove 39 in ring 40. Similarly outlet 61 is connected to opening 61A, passage 61B, and opening 61C so that 60 leads to the two openings 60A and 60C located at opposite ends of the ring 40 and displaced 180° from each other. The same is true of 61, 61A and 61C.

These slotted openings 60A, 60C, 61A and 61C overlie and are open to and register with the several sections of the grooves 39 described in connection with Figure 6.

It should be noted that the openings 60A, 61A, 60C and 61C extend substantially 180° of the inner periphery of the housing member B and that the divisions between aligned passages, for example, 60C and 61C are substantially in the plane of the sectional portion of Fig. 1. That is, these divisions are substantially in the plane of tilting of shaft 28. This location of such divisions is shown clearly in Fig. 7 since the openings 60 and 61 are on opposite sides of the pump and at 90° from the axis of housing portion C (see Fig. 3). This arrangement of cylinder inlets and outlets is important in that it tends to balance out forces tending to tilt shaft 28, that is, tending to rotate the inner portion of the rotor in the plane of the section of Fig. 1. Such balancing of these rotative forces permits the use of a lighter, and therefore more sensitive, spring to resist tilting of the shaft 28.

With the parts in the position shown in Figure 1 and the shaft 28 held so, maximum pumping will occur. However, unless the shaft 28 is so maintained, fluid resistance to piston movement would immediately move the shaft to a position in which its axis is parallel to the axes of the cylinders.

On the other hand, if the shaft 28 is moved so that its axis tilts in the other direction (from that of Figure 1) and so maintained, pumping direction will be reversed. Such reversal of direction of flow is provided for in the present construction and is shown in Figures 1, 2 and 3.

In these figures the complete pump housing is shown as consisting of a third and detachable portion C fixed to the rear end of portion B and into which extends the offset end 28B of shaft 28. This part of shaft 28 has near its end a laterally flattened enlargement 28C and near its extreme end is provided with a recess 28D.

The housing portion C is sufficiently narrow to lie between the inlet 60 and outlet 61 and is fixed to part B by suitable screws or studs 70 and on its face are provided a pair of segment shaped members 71 which extend a short distance into housing portion B and provide guide means for the shaft enlargement 28C in its vertical movement.

Also within the lower portion of part C is a bell crank 72 pivoted at 73 and having both its arms

extending in the same general direction but at a small angle to each other. These arms are indicated at 72A and 72B, the latter being shorter than the former and lying lower and substantially horizontal.

Pivoted to this shorter arm 72B is a link 74 extending up through an opening 75 into a portion of the housing where it is surrounded by a helical spring 76 mounted in compression relation between the wall around opening 75 and a suitable nut 77 on the upper end of link 74.

Pivoted on the long arm 72A is a pin 78 having a conical end adapted to coact with the socket 28D in shaft 28, so that when fluid resistance occurs in pumping, the tendency of shaft 28 to swing downward is resisted by the spring 76 and by suitably adjusting the latter, the maximum delivery pressure can be regulated.

By arranging the crank 72 as shown, that is, placing the short arm substantially at right angles to the link 74 and the arm 72A tilted upward, the build up of the spring as it is compressed is to a great extent compensated for by the increase in the effective leverage of arm 72A.

The amount of downward movement of arm 72A may be adjustably limited by providing link 74 at its bottom end with a foot piece 79 carrying a screw 80 whose end contacts arm 72A as it moves downward a predetermined distance.

In order to regulate the pump delivery in accordance with the back pressure, the housing portion C is provided with a vertical bore 85 directly over the end of shaft 28 and fitted within the bore 85 is an axially bored plug 87, the axial bore being suitably prepared to act as a cylinder within which is slidable a rod-like piston 88. The latter extends from the upper end of the cylinder thus provided to the bottom where it contacts a guide thimble 86 slidable in the lower end of the bore 85, the lower end of plug 87 being reduced in diameter to allow movement of the thimble.

The plug 87 is counterbored at its upper end to provide a small chamber closed by the screw plug 89 and open through lateral passages 90 to a small chamber 91 provided in the housing, the latter chamber being connected through a suitable tube 92 to the outlet 61 of the pump.

With this arrangement, as the back pressure builds up in the outlet 61, the piston 86 forces the end of shaft 28 downward to the position in which it is coaxial with the pump rotor and consequently shortens the piston stroke and lessens the delivery.

It should be noted that the housing portion C is so arranged and constructed that it with its contained parts may be reversed. This is an important feature of the pump. If it should be found desirable to reverse the flow of the pump with the direction of rotation of the rotor remaining the same, the housing portion C and its contained parts is removed, the shaft 28 rotated 180°, the housing portion C replaced in reversed position and the conduit 92 connected to the passage 60. On the other hand, if it is desirable or necessary to reverse the direction of rotation of the rotor, the housing portion C and shaft 28 are both rotated 180° while the conduit 92 remains, or is again, connected to passage 61. Any leakage into the housing may be removed through a suitable drain indicated at 100.

The present application relates to improvement in the construction described and claimed in my copending application Serial No. 509,959, filed on November 12, 1943, Patent No. 2,439,448, April 13, 1948.

Now having described the invention and the preferred embodiments thereof, it is to be understood that said invention is to be limited, not to the specific details herein described and set forth, but only by the scope of the claims which follow:

What I claim is:

1. A multicylinder fluid pump having a rotor consisting chiefly of a plurality of pairs of axially arranged opposed aligned cylinders having pistons therein, a non-rotatable shaft within said rotor, piston actuating means rotatable upon said shaft in a plane normal to the axis of said shaft, delivery pressure actuated means for tilting said shaft whereby to vary the piston stroke, resilient means resisting said tilting, and a pump housing, said housing comprising a portion enclosing said rotor and a separable portion enclosing said tilting means and said resisting means.
2. In a multicylinder fluid pump, a plurality of pairs of axially arranged and aligned opposed cylinders arranged in an annulus to form a rotor, fluid passages opening to said cylinders, a housing surrounding said rotor, and including a spirally arranged passage connecting the ends of a group of said cylinders at one end of the rotor with the ends of a similar group at the other end of said rotor, but 180° from the first group, inlet means opening to said spirally arranged passage, a similarly arranged passage connecting the ends of the remaining cylinders and outlet means opening to said last mentioned passage.
3. In a multicylinder fluid pump, a plurality of pairs of axially arranged and aligned opposed cylinders arranged in an annulus to form a rotor, fluid passages opening to said cylinders, a housing surrounding said rotor, and including a spirally arranged passage connecting the ends of a group of said cylinders at one end of the rotor with the ends of a similar group at the other end of said rotor but at 180° from the first group, inlet means opening to said spirally arranged passage a second spirally arranged passage connecting the ends of the remaining cylinders and outlet means opening to said last mentioned passage, said spirally arranged passages being in the form of hollow ribs on the inner wall of said housing, whereby to strengthen the latter.
4. A multicylinder fluid pump having a rotor consisting chiefly of a plurality of pairs of axially arranged opposed aligned cylinders having pistons therein, a non-rotatable shaft within said rotor, piston actuating means rotatable upon said shaft in a plane normal to the axis of said shaft, means for tilting said shaft whereby to vary the piston stroke, resilient means resisting said tilting, an inlet passage for the cylinders at one end of said rotor communicating with said cylinders throughout substantially one-half of a rotor revolution, an inlet passage for the cylinders at the other end of said rotor and communicating with the latter cylinders throughout substantially the other half of said revolution, outlet passages open to each group of cylinders at the time the inlet passage is open to the other group, the division between the ends of the inlet and outlet passages being substantially in the plane of tilting of said non-rotatable shaft.
5. A multicylinder fluid pump having a rotor consisting chiefly of a plurality of pairs of axially arranged opposed aligned cylinders having pistons therein, a non-rotatable shaft within said rotor, piston actuating means rotatable upon said shaft in a plane normal to the axis of said shaft, means for tilting said shaft whereby said tilting means including a piston actuatable by fluid from the

delivery of said pump, resilient means resisting said tilting, an inlet passage for the cylinders at one end of said rotor communicating with said cylinders throughout substantially one-half a rotor revolution, an inlet passage for the cylinders at the other end of said rotor and communicating with the latter cylinders throughout substantially the other half of said revolution, outlet passages open to each group of cylinders at the time the inlet passage is open to the other group, the division between the ends of the inlet and outlet passages being substantially in the plane of tilting of said non-rotatable shaft.

6. In a multicylinder fluid pump, a tilttable shaft for varying the output of the pump, a fluid actuated piston adapted to tilt said shaft, said piston being actuated by fluid from the pump outlet, and spring means for resisting the action of said piston, said spring means including a spring and a lever of the second class, the long arm of which is operatively connected to said shaft and the short arm of which is connected to said spring, and means for so positioning said lever that the long arm increases its effectiveness and the short arm decreases its effectiveness as said lever is moved by increasing output pressure.
